PRESS ROLL DRIVE

John J. Farrell, Downingtown, Pa., assignor to
Downingtown Manufacturing Company, Downingtown, Pa., a corporation of Pennsylvania

Application September 21, 1933, Serial No. 690,493

20 Claims. (Cl. 92—49)

This invention relates to drives for the presses of paper machinery, and more particularly to a means for driving both rolls of the press while regulating the relative speeds thereof. It has long been recognized that the maintenance of correct relative speeds of the rolls of the main presses, and particularly of the rolls of the first main press of paper machinery, is extremely important in the production of paper.

These rolls must be frequently ground, and as a result of this grinding, any attempt to directly connect the rolls for driving at the same relative speeds either requires changes of the connecting gearing or the use of gears having abnormally long teeth. With either of these constructions there is, however, a surface speed variation as the centers of the rolls approach one another following grinding operations and this variation results in operating troubles, loss of production and increased cost of operation. Due to the inability to obtain proper speeds of the upper roll, it is often necessary to drive the press at much lower speeds than would be possible were the proper relative speeds maintained, due to the fact that with improper relative speeds high speeds of the press will cause crushing of the paper. For this reason, many attempts have been made to provide for compensating means in the driving connection between the rolls with, however, but indifferent success.

An important object of this invention is the provision of means for automatically maintaining the proper relative speeds of the press rolls.

A further object of the invention is the provision of an arrangement of this character which is so constructed that in event of failure of the automatic means the operator can vary the relative speeds during the operation of the machine as desired.

A further object of the invention is the provision in apparatus of this character of an arrangement such that the relative speed is not affected by adjustments of the top roll of the press toward and away from the bottom roll thereof.

These and other objects I attain by the construction shown in the accompanying drawings, wherein, for the purpose of illustration, I have shown a preferred embodiment of my invention and wherein:

Fig. 1 is a side elevation showing a press roll drive and an associated end portion of the press;

Fig. 2 is a section on line 2—2 of Fig. 1;

Fig. 3 is a plan view of the drive;

Fig. 4 is a section on line 4—4 of Fig. 1;

Fig. 5 is a semi-diagrammatic illustration of the automatic control;

Fig. 6 is a front elevation of the timing mechanism;

Fig. 7 is a section on line 7—7 of Fig. 6;

Fig. 8 is a horizontal sectional view through the automatic control; and

Fig. 9 is a section on line 9—9 of Fig. 3.

Referring now more particularly to the drawings, the numeral 10 designates a suitable frame 65 mounting a main drive shaft 11 operated in any suitable manner and driving, through shaft 12, the lower roll 13 of a press P. Frame 10 mounts a second shaft 14 paralleling shaft 11 and connected thereto by change speed mechanism comprising cone pulleys 15 mounted on the shafts 11 and 14 and connected by a belt 16. Shaft 14, through suitable reducing gearing, drives a shaft 17, which shaft 17 is co-axial with the pivot of arm 18 supporting the upper roll 19 of press P. 70 Shaft 17 has a gear 20 thereon meshing with an identical gear 21 on the trunnion of the top press roll 19. It will be obvious that arm 18 may be adjusted to vary the position of the top press roll without changing the relation of the drive 80 gears by which this roll is rotated.

In accordance with my invention, I equip shafts 12 and 17 with pulleys 22 and 23 which are connected by belts 24 with pulleys 25 and 26 of a control unit more particularly shown in 85 Figs. 3, 5 and 8. Pulleys 25 and 26 each comprise an end wall 27 having a projecting hub 28 housed by the pulley and by means of which the pulley is supported from external bearings 29 carried by a suitable supporting bracket 30 90 mounted on frame 10. The end walls 27 of the pulleys are arranged in proximity to one another and have disposed therebetween a friction disc 31 constantly engaging both walls. Pulley 26 is axially threaded at 32 for the reception of 95 the threaded end of a shaft 33, which shaft 33 is splined at 34 in the pulley 25. Shaft 33 is journaled in the bracket and in frame 10 for endwise and rotative movement. Pivoted to the frame 10 is a bell crank lever 35, one arm of 100 which is forked for engagement with shaft 33 and the other arm of which is forked for engagement with a shifting arm 36 controlling shifting fork 37 for belt 16. Fork 37 is at present shown as slidably mounted upon a split tube 105 38 and as having a nut 39 extending through the split of the tube to the interior thereof and having threaded engagement with shifting arm 36. Shifting arm 36 may be rotated by means of a hand wheel 40 or through any other suit- 110

able medium to change the location of fork 37 with relation to the arm.

It will be obvious that as long as pulleys 25 and 26 operate at the same speed, there will be no effect upon shaft 33 except rotation. When, however, one of these pulleys operates at a higher speed than the other, there will be a consequent threading of shaft 33 through the pulley 26, the direction of movement of the shaft depending upon which pulley is driven at the higher speed.

Since the shaft 33 is connected with the fork 37, longitudinal shifting of this shaft will result in movement of the shifting fork and a corresponding change in speed of the input drive for the top roll. Obviously, by properly proportioning pulleys 22 and 23, any desired proportionate peripheral speeds of the press rolls can be obtained and maintained automatically throughout operation. In order that such a construction may readily adapt itself to use in practical paper-making, it is preferred that one of these pulleys be of the expansible type and adjustable in operation, as indicated, such for example as that shown in the patent to F. P. Connors granted September 8, 1931, No. 1,822,584, for Automatic expanding belt pulley. Use of such a pulley will admit of variation of the relative speeds of rolls to suit the requirements of the particular grade of paper which is being run and the preferences of the operator.

Friction disc 31 will, normally, prevent such relative movement in the absence of a positive drive variation. If, for example, one of the belts 24 is broken, this friction disc will serve to rotate the undriven pulley 25 or 26 and prevent any change of adjustment. At this time, speed variations may be regulated through hand wheel 40. Obviously, at any time that the diameter of either of rolls 13 or 19 changes, the size of the driving pulley on the operating shaft of the roll must be correspondingly changed. This may be conveniently effected by making these driving pulleys as indicated.

In order that an optical check on the relative speeds of the press rolls may be maintained, I further provide a timing unit 41 more particularly shown in Figs. 1, 3, 6 and 7. This unit comprises a suitable housing 42 mounting a shaft 43 having a reduced end portion 44. A sleeve 45 is in surrounding relation to the reduced portion of the shaft, and the sleeve and shaft have each secured thereto a worm gear 46. The ends of the sleeve and reduced portion of the shaft project from the housing 42 and the sleeve is equipped with a dial 47 while the shaft is equipped with a pointer 48 co-acting with the dial. Worms 49 engage the worm wheels 46 and are provided with shafts 50 and 51 projecting through opposite sides of the housing 42 where they are equipped with pulleys 52. Shafts 12 and 17 are equipped with pulleys 53 and 54, of which the pulley 54, as in the case of pulley 23, is adjustable as to diameter. No adjustment of the relative sizes of these pulleys is necessary during operation of the machine between treatments of the affected press rolls, but it is merely desirable that the dial and pointer indicate the proportionate peripheral speeds of the press rolls. Accordingly, after any smoothing of the rolls resulting in a reduction of diameter thereof, an adjustment of the proportionate sizes of the pulleys 53 and 54 must be made, following which there will be no necessity for adjustment until the sizes have again been varied. It will be

obvious that the dial 47 and pointer 48 will be rotated at speeds proportionate to the peripheral speeds of the press rolls and that if these roll speeds are equal the pointer will not change its position with relation to the dial. When, however, there is a variation in speed, the pointer will shift upon the dial, indicating such variation. The dial, being graduated, offers a means for very closely checking the relative speeds of the press rolls and, accordingly, admits of exact timing of the rolls.

While I have described and illustrated a particular mechanism, it will be understood that this is merely for the purpose of illustration and that considerable modification can be resorted to without in any manner departing from the spirit of my invention. For example, any conventional driving connection may be provided between shafts 11 and 17 which will permit of a very gradual and accurate variation in the speeds of the shafts. Obviously, with a change in the type of drive, there must be some change in the particular structure of the control mechanism to adapt it to such type of drive. I, accordingly, do not wish to be understood as limiting myself to the particular structure herein illustrated and described except as hereinafter claimed.

I claim:

1. In apparatus of the type described, a pair of rolls, a drive shaft for each roll, means to drive one of said shafts, a gradually variable speed driving connection between the shafts, and means controlled by relative peripheral speeds of the rolls for varying the speed of rotation of the shaft driven through said driving connection. 105

2. In a press, upper and lower press rolls, a drive shaft for each roll, means to drive one of said shafts, a gradually variable speed driving connection between the shafts, means for varying the speed of rotation of the shaft driven through said driving connection, 115 and means to sensibly compare the peripheral speeds of the rolls.

3. In apparatus of the type described, a pair of rolls, a drive shaft for each roll, means to drive one of said shafts, a gradually variable speed driving connection between the shafts, means controlled by relative peripheral speeds of the rolls for varying the speed of rotation of the shaft driven through said driving connection, 120 manual means for varying the speed of rotation of the shaft driven through said driving connection, and means to sensibly compare the peripheral speeds of the rolls.

4. In a press, upper and lower press rolls, a drive shaft for each roll, means to drive one of said shafts, a gradually variable speed driving connection between the shafts, manually operable means for varying the speed of rotation of the shaft driven through said driving connection, 135 and means to sensibly compare the peripheral speeds of the roll.

5. In apparatus of the type described, a pair of rolls, a drive shaft for each roll, means to drive one of said shafts, a gradually variable speed driving connection between the shafts, means controlled by relative peripheral speeds of the rolls for varying the speed of rotation of the shaft driven through said driving connection, 140 and means to sensibly compare the peripheral speeds of the rolls.

6. In a press, upper and lower press rolls, a drive shaft for each roll, means to drive one of said shafts, a gradually variable speed driving connection between the shafts, a longitudinally- 150

- shiftable member determining the speed of rotation of the shaft driven by said driving connection, a pair of rotatable elements relative rotation of which causes longitudinal shift of said member and driving connections between said elements and said rolls. 5 means yieldably resisting relative rotation of the elements. 80
7. In a press, upper and lower press rolls, a drive shaft for each roll, means to drive one of said shafts, a gradually variable speed driving connection between the shafts, a longitudinally shiftable member determining the speed of rotation of the shaft driven by said driving connection, and means controlled by the relative peripheral speeds of said rolls for longitudinally shifting said member. 85
8. In a press, upper and lower press rolls, a drive shaft for each roll, means to drive one of said shafts, a gradually variable speed driving connection between the shafts, a longitudinally shiftable member determining the speed of rotation of the shaft driven by said driving connection, a pair of rotatable elements relative rotation of which causes longitudinal shift of said member, means to rotate said members in accordance with the rotation of said rolls, and means to prevent relative rotation of said rotatable elements upon failure of the rotating means operating either of said elements. 90
9. In a press, upper and lower press rolls, a drive shaft for each roll, means to drive one of said shafts, a gradually variable speed driving connection between the shafts, a longitudinally shiftable member determining the speed of rotation of the shaft driven by said driving connection, a pair of rotatable elements relative rotation of which causes longitudinal shift of said member, means to rotate said members in accordance with the rotation of said rolls, and means frictionally resisting relative rotation of said rotatable elements. 100
10. In a press, upper and lower press rolls, a drive shaft for each roll, means to drive one of said shafts, a gradually variable speed driving connection between the shafts, a longitudinally shiftable member determining the speed of rotation of the shaft driven by said driving connection, a pair of rotatable elements, a threaded connection between one of said rotatable elements and said member, a splined connection between the other of said rotatable elements and said member and means to rotate said elements in accordance with the rotation of the rolls. 105
11. In a press, upper and lower press rolls, a drive shaft for each roll, means to drive one of said shafts, a gradually variable speed driving connection between the shafts, a longitudinally shiftable member determining the speed of rotation of the shaft driven by said driving connection, a pair of rotatable elements relative rotation of which causes longitudinal shift of said member, means to rotate said elements in accordance with the rotation of said rolls, and means yieldably resisting relative rotation of the elements. 115
12. In a press, upper and lower press rolls, a drive shaft for each roll, means to drive one of said shafts, a gradually variable speed driving connection between the shafts, a longitudinally shiftable member determining the speed of rotation of the shaft driven by said driving connection, a pair of rotatable elements, a threaded connection between one of said rotatable elements and said member, a splined connection between the other of said rotatable elements and said member, means to rotate said elements in accordance with the rotation of the rolls, and means to modify the speed of rotation of the driven shaft as determined by said longitudinally-shiftable member. 120
13. In a press, upper and lower press rolls, a drive shaft for each roll, means to drive one of said shafts, a gradually variable speed driving connection between the shafts, a longitudinally shiftable member determining the speed of rotation of the shaft driven by said driving connection, a pair of rotatable elements relative rotation of which causes longitudinal shift of said member, means to rotate said elements in accordance with the rotation of said rolls, means to maintain the longitudinally-shiftable member stationary upon failure of the rotating means of either of said rotatable elements, and manually operable means to modify the speed of rotation of the driven shaft as determined by said longitudinally-shiftable member. 125
14. In a press, upper and lower press rolls, a drive shaft for each roll, means to drive one of said shafts, a gradually variable speed driving connection between the shafts, a longitudinally shiftable member determining the speed of rotation of the shaft driven by said driving connection, a pair of rotatable elements relative rotation of which causes longitudinal shift of said member, means to rotate said members in accordance with the rotation of said rolls, means frictionally resisting relative rotation of said rotatable elements whereby the longitudinally-shiftable member is held against movement upon failure of the rotating means of either of the rotatable elements, and manually operable means to modify the speed of rotation of the driven shaft as determined by said longitudinally-shiftable member. 130
15. In a press, upper and lower press rolls, a drive shaft for each roll, means to drive one of said shafts, a gradually variable speed driving connection between the shafts, a longitudinally shiftable member determining the speed of rotation of the shaft driven by said driving connection, a pair of rotatable elements, a threaded connection between one of said rotatable elements and said member, a splined connection between the other of said rotatable elements and said member, means to rotate said elements in accordance with the rotation of the rolls, means whereby the longitudinally-shiftable member is held against movement upon failure of the rotating means of either of the rotatable elements, and manually operable means to modify the speed of rotation of the driven shaft as determined by said longitudinally-shiftable member. 135
16. In apparatus of the type described, a pair of rolls, a drive shaft for each roll, means to drive one of said shafts, a gradually variable speed driving connection between the shafts, means controlled by relative peripheral speeds of the rolls for varying the speed of rotation of the shaft driven through said driving connection to thereby maintain predetermined relative speeds of said rolls, the last-named means including a part adjustable to determine the relation of the roll speeds. 140
17. In apparatus of the type described, a pair of rolls, a drive shaft for each roll, means to drive one of said shafts, a gradually variable speed driving connection between the shafts, means controlled by relative peripheral speeds of the rolls for varying the speed of rotation of the shaft driven through said driving connection to thereby maintain predetermined relative speeds of said rolls, the last-named means including a part adjustable to determine the relation of the roll 145
75. In apparatus of the type described, a pair of rolls, a drive shaft for each roll, means to drive one of said shafts, a gradually variable speed driving connection between the shafts, means controlled by relative peripheral speeds of the rolls for varying the speed of rotation of the shaft driven through said driving connection to thereby maintain predetermined relative speeds of said rolls, the last-named means including a part adjustable to determine the relation of the roll 150

speeds, said part being adjustable during operation of the rolls.

18. In a press, upper and lower press rolls, a drive shaft for each roll, means to drive one of said shafts, a gradually variable speed driving connection between the shafts, a longitudinally-shiftable member determining the speed of rotation of the shaft driven by said driving connection, a pair of rotatable elements relative rotation of which causes longitudinal shift of said member and driving connections between said elements and said rolls, the driving connection between one of said elements and the associated roll being adjustable to determine the speed of rotation of the associated rotatable element whereby the relative speeds of rotations of the rolls may be adjustably determined.
- 10 19. In a press, upper and lower press rolls, a drive shaft for each roll, means to drive one of said shafts, a gradually variable speed driving connection between the shafts, a longitudinally-shiftable member determining the speed of rotation of the shaft driven by said driving connection, a pair of rotatable elements relative rotation of which causes longitudinal shift of said
- 15 20.
